RAZOR

John N. Graef, West Bend, Wis.

Application June 1, 1949, Serial No. 96,424

9 Claims. (Cl. 30—40)

1

The present invention relates to razors and has for its primary object the provision of a new and improved razor of the type utilizing a strip or ribbon type blade that is movable to bring successive portions of the blade into position for use.

Another object of the present invention is to provide a new and improved razor of the safety type utilizing a movable ribbon type blade which can be made simply and inexpensively, is easily and safely handled in use, is not likely to become dirty and covered or filled with undesired deposits in use, and in which successive portions of the blade can be brought readily into position for use.

A further object of the present invention is the provision of a new and improved razor and a disposable shaving head usable therewith.

A further object of the present invention is to provide a new and improved shaving head which can be disposed of after use and including a desired length of ribbon type blade, which head can be made and packaged inexpensively so that purchasers of razors including both the head and handle may throw away "used" heads when the blade has been fully used.

A further object of the present invention is to provide a new and improved razor including a disposable shaving head in which the blade is permanently sealed in such manner that only the portion being used is exposed and so that there is little likelihood of the user or anyone else being accidentally cut by the blade. This is particularly true because the disposable head has the blade threaded in its before it is sold to the user, and, furthermore, because the blade is made with unsharpened end portions which are respectively exposed prior and subsequent to use of the sharpened portion, whereby the chances of anyone being cut are considerably minimized.

A still further object of the present invention is to provide a new and improved razor including disposable shaving head having a length of ribbon type blade and a handle adapted to be readily but detachably secured to the shaving head and including driving mechanism automatically coupled to blade moving means within the head when the head and handle are operatively secured to each other.

Further objects of the present invention, include the provision of new and improved components of a razor utilizing a ribbon-type of blade among which components may be mentioned an operating and blade moving handle, a shaving head constructed and arranged detachably to be secured to the handle, to be substantially water

2

repellant, and adapted to be thrown away after the blade has been used; and a ribbon type of blade.

In brief, the razor of the present invention is of the type often referred to as a safety razor. It includes a readily detachable handle and shaving head. The shaving head includes a chamber, a shaving portion past which the blade is moved and at which successive portions are exposed for use, the shaving portion being connected to the chamber by entrance and exit portions. The head is permanently sealed except for the entrance and exit and for a handle receiving opening. The shaving head is rendered substantially impervious to water by filling its interior, or at least portions thereof, with a water repellent material such as silicone grease. The head is also constructed and arranged so that it may be made economically and simply, so that it is compact and may readily be used for its intended purpose. As a matter of fact the head may be made so inexpensively that it may be thrown away after use. Furthermore, the head and blade are so constructed and arranged that prior to use an unsharpened portion of the blade is exposed and after use another unsharpened portion is exposed. These unsharpened portions are of but short length, thus providing a greater usable length of blade. The handle constitutes a structural unit including manually operable means for driving the blade, the handle and operating means being so arranged that the operating means is automatically coupled to blade moving means on the head when the handle is secured in place.

Other objects and advantages of the present invention will become apparent from the ensuing description of illustrative embodiments of the invention, in the course of which reference is had to the accompanying drawings, in which:

Fig. 1 is a top plan view of a razor constructed in accordance with the present invention;

Fig. 2 is a bottom plan view of the razor;

Fig. 3 is a longitudinal cross sectional view, the view being taken on the line 3—3 of Fig. 1;

Fig. 4 is an exploded view illustrating the handle detached from the shaving head and illustrating the interior of the head in a section taken along the line 4—4 of Fig. 3;

Fig. 5 is a front elevational view of the razor;

Fig. 6 is a fragmentary view of the blade used in the razor;

Figs. 7 and 8 are elevational views, partly in section, of blade supply and take-up spools, respectively; and

Fig. 9 is a side elevational view, partly in section, of a modified form of razor.

Referring now to the drawings, and first particularly to Figs. 1 to 5, inclusive, it may be noted that the razor of the present invention, which has been indicated as a whole by reference character 10, is of the well known safety razor type. It includes, as best indicated in Fig. 4, a separable shaving head 12 and handle 14, both of which are of novel construction, as will appear shortly.

The shaving head 12 is so constructed and arranged that it can be used for a considerable period of time and then thrown away. It includes a strip or ribbon type blade, hereinafter referred to as a ribbon type blade, and which is indicated by the reference character 16. It is preferably sharpened at one edge, as indicated by reference character 18; see Fig. 6, for the major portion of its length. The ends 20 are, however, unsharpened for, but a short portion, to prevent any likelihood of accidental cutting prior to and after use of the entire blade. The blade is also provided with indicia which may take the form of numbers and which cooperate with a notch 22 or other indicia at the front of the shaving head to facilitate proper movement of the blade to bring successive portions into proper position for use.

The blade 16 is mounted within a chamber 24 inside the head and which chamber may be called a blade storage chamber. In order to prevent accidental cutting, the blade is permanently and substantially sealed within the chamber. This results from the fact that the only openings to the chamber are a handle receiving opening 26 at the rear of the head and the openings 30 and 32 at the front of the shaving head, which openings may well be defined as blade entrance and exit, respectively, and which lead to and from a shaving portion 34 at the front of the shaving head whereat the blade is exposed for use. Better to hold the exposed portion of the blade in tension and to prevent the ingress of water to the interior of the chamber, the entrance and exit to the shaving portion communicate with the chamber through curved passageways 36 and 38 of considerable length and dimensioned closely to receive the blade.

In order to facilitate construction of the blade guiding passages 36 and 38, the passages may be formed by arcuate portions 40 and 42 of a head housing section 44 which, together with an opposed housing section 46, define the head and chamber 24. Section 44 has a peripheral wall 46 including the aforementioned portions 40 and 42, a front wall 48 defining the front wall of the chamber and a transversely extending support for the blade 16. The blade passages 36 and 38 are defined by the arcuate wall portions 40 and 42 and generally circular inserts 50 and 52, whose outer walls are concentric with the inner walls of portions 40 and 42. The inserts, which may be made separately for convenience, are mounted upon spaced tubular upstanding supports 54, preferably made integral with the housing section 44. It may be well to note at this point that the head can be made from some suitable material such as aluminum, magnesium or plastic, plastic being preferred at least at the present time and being used in the embodiment of Figs. 1 to 8.

The upper housing section 46 is permanently secured to the lower section as by cement or the like, after the blade has been placed in the chamber 24, as will be described shortly. Proper location

and assembly of the upper section on the lower is facilitated by providing the upper section with a downwardly extending annular boss 56 adapted rather closely to fit around an upstanding spindle 58 on the lower section, the purpose of which will be described hereinafter.

The shaving portion 34 at which successive portions of the blade are exposed includes a comb guard 60 with enlarged and forwardly projecting guide ribs 61 on the lower housing section, and a cooperating downwardly extending flange 62 on the upper section. The latter not only cooperates with the comb, but it serves to hold the exposed portion of the blade in place during the shaving operation, it defining a blade receiving channel with the support 48.

A considerable length of blade is mounted in the chamber 24 upon blade supplying and take-up means. The blade supplying means may take 20 the form of a spool 64 and the takeup means may take the form of a spool 66. The spools are mounted for rotation about the previously mentioned spindle 58 and a second spindle 68 spaced from the former and in line with the handle. 25 The two spindles are easily constructed as integral parts of the lower housing section 44 and in order to provide a compact assembly holding a considerable length of blade they are provided with reversed flanges.

30 The supply spool includes a hub-like portion 70 rotating about and located by the boss 56 in the upper housing section. It is provided at its upper end with a horizontal flange 72 abutting against the underside of the upper housing section, and, in order to prevent dulling of the razor blade, this flange is located so as to abut against the unsharpened upper edge of the blade. The sharpened edge of the blade may abut lightly or be spaced a short distance from 40 the bottom of the chamber 24.

The supply and takeup spools are both constrained against rotation in reverse or backward direction by individual one way clutching means, the one way clutching means for the supply spool including a helical spring 74 having one end 76 mounted in a small opening in the boss 56, while the wound portion of the spring bears against the interior of the spool itself. The spring is confined within the spool by the boss 56 and by 50 the end flange 78 of the spool.

The takeup spool 66 includes the outwardly extending lower flange 80, the hub portion 82 and the upper inwardly extending flange 84 fitting closely about the reduced diameter upper 55 end of spindle 68. The hub portion is journaled to fit closely about an enlarged portion 86 at the base of spindle 68. The movement constraining spiral spring 88 has one end 90 located in a small opening in the enlarged portion 86, while the remainder of the spring bears against the interior of the spool and is confined therein by the flange 84.

The movement constraining springs associated 65 with the supply and takeup spools assist in holding the blade taut and they also serve to prevent reverse movement of the blade thereby to prevent movement of a used portion of the blade back into position for use. The springs are so arranged that they release the spools for movement when they are turned counterclockwise, as viewed in Fig. 4. The clutching arrangement also serves to keep the blade in its original position after manufacture and before use by a person using the razor.

70 In order to prevent undesired ingress of water

and dirt to the chamber 24, the passageways 36 and 38, as well as the portions of the chamber near thereto, or if desired, the entire chamber, may be filled with a water repellent material, such as silicone grease, which is now available on the market and which includes an antiwetting agent.

In accordance with another feature of the present invention, the shaving head is arranged automatically to be drivingly coupled to manually operable blade moving means associated with the handle when the two are joined. Referring now more particularly to Figs. 3 and 4, it may be noted that the handle 14 includes a projecting externally threaded portion 92 adapted to be threaded into and secured to the interiorly threaded opening 26. The handle includes also driving means in the form of a bevel gear 94 adapted to engage blade driving means in chamber 24 when the handle is secured in place. The maximum diameter of gear 94 is less than the minor diameter of threads 92 so that insertion can readily be effected.

The blade driving means advantageously takes the form of a downwardly facing crown gear 96 formed integrally with the lower flange 80 of the takeup spool. Not only is the construction simple and inexpensive, but the driving means can be made and coupling effected in a very simple manner.

The blade driving bevel gear 94 is formed at or secured to one end of an operating shaft 100 rotatably mounted within a sleeve 102 to the exterior of which a fixed handle portion 104 is suitably affixed as by spaced knurling 106 at the exterior of the tube. The projecting portion of the tube may also have on it the previously referred to threaded portion 92, whereby the handle is secured to the shaving head.

At the outer end of the fixed handle portion 104 of the handle there is located a manually operable blade moving knob 108 which forms in effect a continuation of the handle in so far as appearance is concerned. The knob 108 is affixed to the shaft 100 as by the splines 110.

In order even more to insure against undesired reverse movement of the razor blade, the operating knob 108 is provided with means constraining it against movement in one direction. This means may take the form of a clutch or a brake, indicated generally by the reference character 112 and including a helical spring 114 encircling the enlarged end 116 of the tube 102. The end 118 of the spring projects into a small opening 120 in the knob, the arrangement being such that the spring 114 is loosened upon the portion 116 of the tube when the knob is turned in the correct direction, counterclockwise, as viewed from the end.

Holding of the razor is facilitated by providing the fixed and rotatable handle portions 104 and 108 with longitudinal grooves 122.

In the embodiment of the invention being described, the shaving head and handle is made of plastic material, which may be transparent in nature. However, and as also earlier indicated, metal may be used for both and a razor utilizing metal has been illustrated in Fig. 9. When the razor is made of metal there is no need for the tubular insert corresponding to tube 102 and the blade moving shaft 100 may be journaled directly in a fixed handle portion 130 having an externally threaded portion 131 of reduced diameter, adapted to be threaded into and secured to the shaving head. A somewhat different manually

operable knob 132 is also used. It includes a reduced diameter portion 134 extending into but spaced slightly from an opening 136 in the handle portion 130. It is surrounded by a clutch spring 138, having its end 140 secured in a small opening in the handle portion 130. In this arrangement as in the earlier described one, reverse movement of the control knob 132 is prevented by tightening of the spring 138, this time against the part 134 of the knob.

From the foregoing detailed description of the invention it may be noted that the razor may be made inexpensively, that it is compact, may be easily handled in use, is safe, and that the disposable head may be thrown away after it has served its purpose. As a result, the head does not become dirty and greasy and covered with deposits as is the case with most safety razors unless they are cleaned thoroughly and frequently.

In the construction of the device the shaving head is made of the two sections, but before they are joined and permanently sealed, the blade is wound upon the supply spool with one end permanently secured to this spool and the other end to the takeup spool, and is threaded through the passages 36 and 38 so that unsharpened portion 20 is exposed in the shaving portion 34. When thus assembled, the housing sections are sealed in a suitable manner and the head is ready for shipment. If desired, the chamber 24 in the head may be partly or entirely sealed with water repellent material prior to sealing.

A person desiring to use the razor may obtain both the handle and one or more shaving heads. The head may be easily connected to the handle, all that is necessary being the threading of the handle on the head after which the razor is ready for use.

To use the razor, the knob 108 is turned to rotate the takeup spool enough to bring the first sharpened portion of the blade into shaving position, this being indicated by the registry of the numeral 1 with the indicating notch 22. After this portion has been dulled by use, successive portions of the blade may readily be moved into shaving position. Undesired reverse movement of the blade is prevented by the three clutches, two of which are in the shaving head and the third in the handle. The two in the shaving head also prevent undesirable movement of the blade prior to its use and when the razor is not intentionally adjusted to bring a new portion of the blade into position for use. The clutches in the head also serve to keep the blade taut and they are assisted in maintaining the blade taut by the curved construction of the entrance and exit passages 36 and 38 leading to and from the shaving portion 34.

While the present invention has been described in connection with illustrative embodiments thereof, it should be understood that the details thereof are not intended to be limitative of the invention, except in so far as set forth in the accompanying claims.

Having thus described my invention, what I claim as new and desire to secure by Letters Patent of the United States is:

1. A razor including a shaving head having a chamber, a ribbon type blade in said chamber and movable past a shaving portion where it is exposed for use, said head including a handle receiving aperture having an internally threaded portion, blade moving means in said chamber including a downwardly facing crown gear open to

said aperture, and a handle having an externally threaded portion adapted to be secured to the threaded portion of said aperture and including manually rotatable bevel gear adapted to mesh with said crown gear when the handle is secured to said head.

2. As a new article of manufacture, a disposable shaving head having a ribbon type blade storage chamber and a shaving portion at which the blade is exposed having entrance and exit apertures communicating with said chamber, a ribbon blade in said chamber threaded past said shaving portion through said entrance and exit apertures, blade supply and takeup spools in said chamber, said shaving head being substantially permanently sealed except for said apertures and a handle receiving aperture, driving means for said takeup spool and said takeup spool driving means communicating with said handle receiving aperture.

3. A razor handle for use with a shaving head having a ribbon type blade, including a first portion adapted detachably but fixedly to be secured to the head, a blade moving portion movably mounted in and projecting through one end of said first portion, means including one way movement constraining means connecting said two portions whereby said blade moving portion is constrained against movement in one direction, an externally threaded portion at one end of said first portion surrounding at least a portion of the projecting part of said blade moving portion, and a bevel gear secured to the projecting part of said blade moving portion, said gear having a maximum diameter less than the minor diameter of the thread.

4. A razor handle for use with a shaving head having a ribbon type blade, including a first portion adapted detachably but fixedly to be secured to the head, a blade moving portion movably mounted on said first portion, and means including one way movement constraining means connecting said two portions whereby said blade moving portion is constrained against movement in one direction, said movement constraining means including a helical spring surrounding a portion of said first portions and having one end secured to said blade moving portion.

5. A shaving head including opposed housing sections secured together to form a chamber, one of said sections including integral spaced spindles and a peripheral side wall and the other including structure engaging said spindles and abutting against said wall, said engaging structure including at least one circular boss fitting closely about the unattached end of one of said spindles, a circular enlargement at the base of the other of said spindles, and blade supply and take-up spools surrounding said spindles, one having a hub fitting closely about said circular boss and the other a hub fitting closely about said enlargement.

6. A shaving head including opposed housing

sections secured together to form a chamber, one of said sections including integral spaced spindles and a peripheral side wall and the other including structure engaging said spindles and abutting against said wall, said engaging structure including at least one circular boss fitting closely about one of said spindles, a circular enlargement at the base of the other of said spindles, flanged blade supply and takeup spools surrounding said spindles, one having a hub fitting closely about said circular boss and the other a hub fitting closely about said enlargement, and spool movement constraining means inside said spools having helical portions engaging the hubs of the spools and end portions secured to said boss and enlargement, respectively.

7. A shaving element for a razor of the type utilizing a ribbon type blade including a blade storage chamber, blade supply and takeup spools mounted in said chamber, said spools having flanges at opposite ends only and said flanges being in overlapping relation, the flange of the takeup spool having a downwardly facing crown gear.

8. A razor including a shaving head having a chamber, a ribbon type blade in said chamber and movable past a shaving portion where it is exposed for use, said head including a handle receiving aperture, blade moving means in said chamber including a downwardly facing crown gear open to said aperture, and a handle having an end portion adapted to be inserted within said aperture and including a manually rotatable bevel gear adapted to mesh with said crown gear when the handle is inserted within said aperture.

9. A razor handle for use with a shaving head having a ribbon type blade, including a first portion adapted detachably but fixedly to be secured to the head, a blade moving second portion movably mounted on said first portion, and means including one way movement constraining means connecting said two portions whereby said blade moving portion is constrained against movement in one direction, said movement constraining means including a member surrounding one of said portions and having one end secured to the other of said portions.

JOHN N. GRAEF.
